US00D583931S

(12) United States Design Patent
Rosenkranz et al.

(10) Patent No.: **US D583,931 S**
(45) Date of Patent: **** Dec. 30, 2008**

(54) NASAL MASK

(75) Inventors: **Mark E. Rosenkranz**, Parma, OH (US);
Tom Sprinkle, Rocky River, OH (US);
Mary B. Whitesel, Grafton, OH (US);
Valentine A. Hodos, Cleveland, OH (US);
Neal J. Curran, Lakewood, OH (US)

(73) Assignee: **Invacare Corporation**, Elyria, OH (US)

(**) Term: **14 Years**

(21) Appl. No.: **29/203,730**

(22) Filed: **Apr. 16, 2004**

Related U.S. Application Data

(63) Continuation-in-part of application No. 29/157,682, filed on Mar. 22, 2002, now abandoned.

(51) **LOC (8) Cl.** **29-02**

(52) **U.S. Cl.** **D24/110.4; D24/110.1**

(58) **Field of Classification Search** **D24/110.1, D24/110.4, 110.5**

See application file for complete search history.

(57) CLAIM

The ornamental design for a nasal mask, as shown and described.

DESCRIPTION

FIG. 1 is a perspective view of a first embodiment of a nasal mask showing the new design;

FIG. 2 is a side view thereof;

FIG. 3 is a front view thereof;

FIG. 4 is other side view thereof;

FIG. 5 is a back view thereof;

FIG. 6 is a bottom view thereof; and

FIG. 7 is a top view;

FIG. 8 is a perspective view of a second embodiment of a nasal mask;

FIG. 9 is a side view thereof;

FIG. 10 is a front view thereof;

FIG. 11 is other side view thereof;

FIG. 12 is a back view thereof;

FIG. 13 is a bottom view thereof;

FIG. 14 is a top view;

FIG. 15 is a perspective view of a third embodiment of a nasal mask;

FIG. 16 is a side view thereof;

FIG. 17 is a front view thereof;

FIG. 18 is other side thereof;

FIG. 19 is a back view thereof;

FIG. 20 is a bottom view thereof; and,

FIG. 21 is a top view.

The portions of the Figures shown in phantom lines are not part of the claimed design but are for illustration only.
